UNITED STATES PATENT OFFICE.

FREDERICK H. HURLBUT, OF ALAMEDA, AND THOMAS W. MUNROE, OF SAN FRANCISCO, CALIFORNIA.

GAS-ENGINE.

No. 820,497.

Specification of Letters Patent.

Patented May 15, 1906.

Application filed February 24, 1905. Serial No. 247,105.

To all whom it may concern:

Be it known that we, FREDERICK H. HURLBUT, residing at Alameda, in the county of Alameda, and THOMAS W. MUNROE, residing at San Francisco, county of San Francisco, State of California, citizens of the United States, have invented certain new and useful Improvements in Gas-Engines; and we hereby declare the following to be a full, clear, and exact description of the same, reference being had to the accompanying drawings, forming a part of this specification.

This invention relates to explosive or internal-combustion motive engines impelled by gas or volatilized hydrocarbons and to certain useful improvements in such engines, as described in the following specification and illustrated by drawings that form a part of the same.

Our improvements consist in various features of a constructive and operative nature that cannot well be defined without the aid of the drawings and will be set out in a description to follow and by claims at the end of this specification.

The objects of our invention are to attain in an economical manner what is called a "two-cycle" action of such engines, to regulate the power of the same, and provide for quickly reversing their rotative motion, as is required in marine propulsion, hoisting, and like purposes.

Referring to the drawings, Figure I is a front elevation of a motive engine constructed according to our invention, partially broken away to disclose interior parts; Fig. II, a plan view of the same engine, also broken to show interior passages; Fig. III, an end view of the same engine, partly broken to disclose interior parts, the fly-wheel and other parts mounted on the front end of the crank-shaft being omitted. Fig. IV is another end view of the same engine, partially in section, showing in part the ignition devices, a section through the charge-compressing engine, the pistons and induction-valves for the same; Fig. V, an enlarged front view of the devices for controlling ignition and reversing the engine. Fig. VI is a corresponding view to Fig. V, showing the same parts in side view and partial section and further illustrating the igniting and reversing devices; Fig. VII, a detail diagrammatic front

view showing a part of the igniting and reversing devices; Fig. VIII, another detail diagrammatic front view of the same devices with the same parts in a different position; Fig. IX, a third view of the same parts, showing them in a still different position; Fig. X, a section through one of the valves to regulate the by-passing or circulation of the surplus gas or fuel.

Stated in general terms, our invention consists in two single-acting motive cylinders and pistons positively connected to a crank-shaft and between these, operated by the same crank-shaft, a double-acting charge mixing and compressing cylinder and piston, the displacement or volume of which exceeds that of the motive cylinders and supplies gas or fuel at a pressure or volume corresponding to the resistance or work to be performed by the motive engines, an automatic means of regulating the pressure and volume of the gas or fuel thus supplied and the power of the motive engines by means of by-pass or circulating connections controlled by centrifugal regulating devices that return and conserve gas or fuel in excess of that burned in the motive cylinders and required by the load or resistance, also an adjustable means of causing or permitting a like circulation, conservation, and return of unused gas or fuel when stopping, starting the engine, and other operating conditions of the engine permit such surplus circulation and conservation of the gas or fuel furnished by the mixing and compressing cylinder.

Our invention further includes an adjustable means of controlling the point of ignition, lead, and retardation and cessation of the same. Consequently all motions of the engine, including the reversal of the course of rotation and at the same time and by the same and connected devices control the circulation and conservation of surplus gas or fuel, the whole of this latter-named apparatus operating in a manner analogous to what is known as "link-gearing" for engine slide-valves, the engines being dual except as to the double-acting compressing cylinder and piston, and the whole constituting an organized and interdependent motive engine adapted for marine propulsion and like uses, especially those that involve reversal of the engine's rotation.

Referring to the drawings, 1 is the usual base-frame on which is mounted the crank-shaft 2 in the bearings 3.

4 and 5 are motive cylinders supported on 5 the base-frame 1 by struts 7 and provided with pistons 8 and connecting rods or links 9, attached to opposite cranks 10 and 11 in the shaft 2 in the usual manner of double engines of this type.

10 The motive cylinders and contiguous parts exposed to high temperature are protected by cooling-water supplied through the pipe 12 and circulating in the several chambers marked 0. 13 is the supply-pipe for gas or 15 fuel, and 14 the exhaust-pipes for the spent vapor or gas discharged through the parts or passages 6 when the pistons 8 pass below these, as shown in Fig. I.

Between the motive cylinders 4 and 5 and 20 integrally constructed therewith we provide a double-acting charge-compressing pump or engine 15, having a piston 17, piston-rod 18, cross-head 19, connecting-rod 20, attached to a crank 22 in the shaft 2, as shown in Fig. I.

25 The mixing and compressing piston 17 is double acting and draws in its charges of gas or fuel alternately through valves 28 and 29 and passage 30. On its upward stroke this piston discharges its contents of gas or fuel 30 through the valve 23, the passage 24, and valve 32 into the motive cylinder 4, as indicated in Fig. II. On its downward stroke it discharges into the motive cylinder 5 through the valve 25 and passage 27, as shown in Figs. 35 II and IV.

The inlet or induction valves 28 and 29 for 40 the compressing-cylinder communicate at the top and bottom with the passage 30, as shown in Fig. IV, and this passage is in communication by means of the supply-pipe 13 with a carburetor or other source of gaseous fuel, so 45 the compressed charges from the engine 15 are on the upward and downward stroke thereof discharged wholly or partially and alternately into the motive cylinders 4 and 5, as before explained.

The displacement volume of the compressing and mixing piston 17 exceeds that of either of the motive pistons 8, including the 50 passages leading thereto, by so much as will determine the maximum pressure required for the compressed charges of fuel. This difference in volume or displacement is in practice made from ten to twenty per cent., the 55 proportion not requiring to be exact because of any surplus or overcharge being returned and not consumed, as will be hereinafter explained.

The crank 22 stands in a definite relation to 60 the motive cranks 10 and 11, being about fifty-six degrees behind the crank of the motive piston being charged and one hundred and thirty degrees in advance of the other crank and changes this relation, respectively, as the 65 engine is running right or left. As shown in

Fig. III, the crank 22 of the compressing-engine 15 stands about fifty degrees behind the crank 10 of the motive engine 5 when the engine is running forward or, as indicated by the arrow, the top part of the compressing-engine supplying a charge of fuel to the motive engine 5 after the piston 8 of the latter has moved upward sufficiently to close the exhaust-ports shown at 6 in Fig. I.

If the engines are reversed to run in the opposite direction, then the crank 22 has a similar relative position in respect to the crank 11 of the motive engine 4 that it had to the crank 10 of the motive engine 5 when running in the opposite direction, and the charge of fuel-gas from below the piston 17 is supplied to the motive engine 4. In this manner it will be seen that when the engine is running in either direction the advance of the crank 22 maintains a like relation to one or the other of the cranks 10 or 11, respectively. This feature has especial reference to the devices for reversing and controlling the engine and igniting the charges in the motive cylinders, as will be hereinafter explained.

Referring now to the regulation of the engine's power and the consumption of fuel charges drawn in and discharged by the mixing and compressing piston 17, such parts of the charges as are not required instead of wholly entering the motive cylinders 4 and 5 are forced back through the pipes 35 and 37 to the pipe 13 and to the source of supply or are circulated without being consumed. The charges of fuel-gas thus delivered to the motive engines enter at their tops and being diffused in a circular form in passing the induction-valves 25 and 32 are spread around the interior of the cylinders, driving ahead and expelling spent gas that may have remained therein.

The surplus of compressed fuel that may be returned or circulated is regulated by two separate means employed together or independently, according to the nature of the work to be performed by the engine. If the engine is to operate against a variable load or resistance, but at a uniform rate of revolution, a regulating or throttling valve 39 is placed in the circuit formed by the pipes 35, 37, and 38 and is operated by a centrifugal regulator 40 in the usual manner of such apparatus.

When the rate of the engine increases, the regulator 40 opens the valve 39 accordingly, so that charges of fuel compressed and discharged by the piston 17 may in part or wholly be circulated, thus attenuating the volume and force of the charges in the motive cylinders 4 and 5 and, if required, reducing the pressure of the fuel-gas below the point of ignition, so that none will be wasted.

For marine propulsion and other cases where the resistance or load of the engine is constant, the centrifugal regulating devices

are not essential, but may be usefully employed to prevent the racing of propeller-screws or excessive speed of the engine in any case; but another means of regulation is provided.

5 Besides the regulating-valve 39 we employ a second double-acting or dual valve 42 (shown enlarged in Fig. X) to control the consumption and circulation of surplus gas or 10 fuel. This valve, which will be further explained, acts automatically or by connection with the igniting and reversing devices, which are combined and interdependent. To 15 explain these latter devices, they are the same for each motive engine with like functions and movements and are adjusted in unison with respect to the two motive engines and the direction of their rotation by means of a cross-shaft 43, operated by a 20 hand-lever 44, (indicated by the dotted lines *a* in Figs. VII, VIII, and IX.) This lever is locked at various points by a notched segmental rack 45 in the manner of link-motion gearing for engine slide-valves and has like 25 purposes.

Fastened at the ends of the shafts 43 are segmental toothed quadrants 47, that mesh into and turn or oscillate the gear-wheels 48, mounted loosely on a sleeve around the short 30 shaft 49, as shown most clearly in Figs. VI and VII. This shaft 49 is mounted in a bracket 54 and is driven by a pinion 50, the number of teeth and relative rates of revolution being as one to two of the crank-shaft 2.

35 The gear-wheel 48 turns on a sleeve 53, formed on the bracket 54, as shown in Fig. VI, and to the side thereof is attached an insulated disk 55, in which are inserted two opposite diametrically-movable electrodes or 40 contact-pins 59, which as the disk 55 revolves are pressed inward during a portion of their revolution by the insulated segmental guide 58 while they are passing over its arc and when pressed inward to touch or bear 45 upon the disk 60, each pair contacting simultaneously the small metal bars or rods 61, embedded in the face of this revolving insulated member 60, which is fastened on the end of the shaft 49, as shown in Fig. VI.

50 To avoid a positive fit between the pin 59 and the insulated parts 58 and 60 and to secure an elastic contact, they are preferably made in two parts to contact in the center, a spring 56 being provided to hold them 55 slightly apart and keep the electric circuit open until the outer pin engages the guide 58. This is a constructive expedient to avoid undue pressure at the ends of the pins that might occur if they were in one piece and 60 rigid. Their operation is, however, the same in either case. This closes the electric circuit between the contacting pins or electrodes 59 and between the wires 62 and 63, held in the posts 66, that connect to part 58, 65 to the igniting devices shown and an elec-

tric battery in the usual manner and as indicated in Figs. I and IV. When either of the pairs of pins or electrodes 59 come in contact with the bars 61, the electric circuit is closed between the pins, causing a spark and ignition of the charges in the corresponding motive cylinders 4 and 5 in the usual manner of electrical ignition and not requiring description beyond that of the diagram in Fig. IV. In so far as these devices perform electrical 70 ignition of the charges in the motive cylinder 4 and 5 their function is plain and corresponds to common practice; but their varying relation to the position of the cranks of the motive and compressing cylinders and in 75 controlling and reversing the course of the engine's rotation their functions are peculiar 80 and important.

The contact or circuit-closing pins 59 are dual, disposed diametrically opposite in the 85 insulated member 60, and the position of these the circuit-closing bars 61 and of the segmental guide 58, with the active and inert parts of their revolution, all have definite relation to certain positions of the two oppositely-placed cranks 10 and 11 and the crank 22, constituting a combination not easy to 90 explain in words.

Referring to Figs. VI, VII, and VIII, where the dotted lines *a* represent the lever 44, it must be kept in mind that the contacting segment or guide 58, which occupies about ninety degrees of arc or forty-five degrees each way, has no time function except that it covers the range of ignition pressing 95 inward and contacting the pins 59 each way throughout this range. The parts 58 and 61 may be said to maintain a constant relation in respect to the shafts 49 and 2, so the variable or time function becomes a sequence of 100 the position of the contacting pins 59 between these parts 58, 59, and 61 and of the adjustment of the latter about the axis of the shaft 49 by means of the gear-wheel 48, segmental lever 47, and the operating-lever 44. 110

There being two oppositely-placed pairs of the contacting pins 59, it is obvious that their motion oppositely about the axis of the shaft 49 must produce like results when revolving in either direction or when the engine is reversed, also that when neither of the contacting pins 59 is between the segmental guide 58 and the circuit-closing bars 61 ignition will cease and the engine will stop operating in so far as control in the same manner as 115 in the case of valve-link-gearing apparatus for steam-engines. If, for example, the shaft 2 and the shaft 49 are revolving in the direction indicated by arrows in Fig. VII and the lever 44 is set on the line *a* in notch 65, 120 then the pins 59 will be pressed inward at 69 and will jointly contact the circuit-closing bars 61, so as to ignite the charge in one of the motive engines 4 or 5 at approximately 125 ninety degrees after the engine has passed 130

its center or is at its quarter-stroke. If, then, this lever is moved to the notch 67, the position of the pins 59 will be advanced and ignition will take place on the center or extreme 5 upper stroke of the motive engine in circuit. If the lever is again moved to the notch 68, ignition will again be advanced or given "lead," as it is called, ignition taking place before the center is reached or before the pistons 8 have reached their extreme upper 10 stroke. If, then, the lever is moved back to line c, the pins 59 will not contact the part 58 and circuit-closing bars 61 at the same time and the engine will stop for want of igniting 15 the charges.

The reverse motion of the lever 44 to the notches 70, 72, and 73 brings into action the opposite pair of contacting pins 59, producing the converse of what has been explained, 20 and, as shown in Fig. VIII, where the motion is reversed, as indicated by the arrows, the notches 70, 72, and 73 showing positions of the lever 44 for ignition at different points as before.

25 The diagram Fig. IX shows the position for lead or advanced ignition when the movement of the engine is as indicated, this occurring when one pair of the contact-pins 59 are opposite to or converging with the mark 74. 30 in the center of the segmental guide 58.

Referring to the valve 42, which is of the piston type, as shown enlarged in Fig. X, it is double-acting and double-ported, as shown, the passages 77 in the valve registering with 35 the one, 78, in the walls on the up and down movements and as the engine is moving right or left. This valve is operated by a stem 79 and a crank or lever 80 on the shaft 43, coincidently, with motions of the lever 44 40 as is opened when this lever is locked in or is between the notches 65 and 67 and the notches 70 and 72 in the bar 45. When this valve 42, which connects the pipes 37 and 38, is open, it permits circulation or return of the charges 45 compressed by the piston 17 gradually and in proportion to its movement between the points named and has for its object attenuating or weakening the charges and the impulses of ignition when the engine is stopped, 50 started, or reversed. It has also the further object that when closed it permits the compressing-engine 15 and the piston 17 to maintain full-pressure charges in the motive cylinders 4 and 5 and in chambers and passages 55 connecting therewith, so the engine will be prepared to start at any time and in either direction with a full charge.

It will be seen that the functions of this valve 42 do not interfere with the one, 39, operated by the regulator 40 and that both can be employed when the purposes to which the engine is applied requires their joint control.

To the left in Figs. I and II is shown gearing for transmitting the power of the engine 65 to a screw-propeller or other shaft 82, en-

gaged to the engine-shaft 2 by a friction-clutch 83; but any other suitable means of transmission can be employed.

Having thus explained the nature and objects of our invention and means for its application in practice, what we claim as new, and desire to secure by Letters Patent, is—

1. In a gas-engine, two single-acting motive cylinders, with pistons connected to oppositely-placed cranks on a common shaft, a double-acting compressing-cylinder between said motive cylinders, having a displacement volume greater than either of said motive cylinders, a piston in said compressing-cylinder connected to a crank on the common 75 shaft at an angle to the motive-piston cranks, inlet-valves in said compressing-cylinder at both ends, pipes and passages from a fuel-supply to said inlet-valves, a valve at each end of said compressing-cylinder with 80 passages leading to each motive cylinder respectively, a check-valve in each motive cylinder at the terminus of each of said passages, circulatory passages between the compressing-cylinder and the motive cylinders, and a 85 regulating-valve in said circulatory passages, substantially as specified.

2. In a gas-engine, two single-acting motive cylinders, with pistons connected to oppositely-placed cranks on a common shaft, a 95 double-acting compressing-cylinder between said motive cylinders, having a displacement volume greater than either of said motive cylinders, a piston in said compressing-cylinder connected to a crank on the common 100 shaft at an angle to the motive-piston cranks, inlet-valves in said compressing-cylinder at both ends, pipes and passages from a fuel-supply to said inlet-valves, a valve at each end of said compressing-cylinder with 105 passages leading to each motive cylinder respectively, a check-valve in each motive cylinder at the terminus of each of said passages, circulatory passages between the compressing-cylinder and the motive cylinders, a regulating-valve in said circulatory passages, 110 igniting means, and a double-acting regulating-valve operating in connection with said igniting means, substantially as specified.

3. In a gas-engine, two single-acting motive cylinders, with pistons connected to oppositely-placed cranks on a common shaft, a double-acting compressing-cylinder between said motive cylinders, having a displacement volume greater than either of said motive cylinders, a piston on said compressing-cylinder connected to a crank on the common 115 shaft at an angle to the motive-piston cranks, inlet-valves in said compressing-cylinder at both ends, pipes and passages from a fuel-supply to said inlet-valves, a valve at each end of said compressing-cylinder with 120 passages leading to each motive cylinder respectively, a check-valve in each motive cylinder at the terminus of each of said passages, 125

circulatory passages between the compressing-cylinder and the motive cylinders, a regulating-valve in said circulatory passages, igniting means, a double-acting regulating-
5 valve operating in connection with said igniting means, and a reversing-gear in connection with said igniting means, substantially as specified.

4. In a gas-engine, two single-acting motive and a double-acting charge-compressing piston connected to a common crank-shaft, a second shaft connected to and driven by the same crank-shaft at half its speed, around this second shaft an adjustable insulated
10 disk or collar provided with oppositely-placed pairs of electrodes or contacting pins, electric wires connecting from these pins to an electric battery and to the combustion-chambers of the motive pistons, means to
15 connect the inner ends of these contacting pins and close the circuit at different points of the stroke of the motive pistons, substantially as specified.

5. In a gas-engine, two single-acting motive pistons, a double-acting charge-compressing piston, all connected to a common crank-shaft, means to supply and regulate fuel charges for the motive engines, a second shaft geared to the crank-shaft to revolve at
20 half its rate, on this shaft a revolving insulated disk provided with two diametrically opposite circuit-closing bars 61, concentric with this insulated disk a segmental insulated member, wires therefrom to an electric
25 battery, spark-coils and the combustion-chambers of the motive cylinders and between the rotary insulated disk and concentric insulated member 58, pairs of movable contacting and circuit-closing pins 59 mounted radially and oppositely in a revolvable insulated disk and adjustable by hand, substantially as specified.

6. In a gas-engine, two single-acting motive pistons and a double-acting charge-compressing piston connected to a crank-shaft, second shafts for each motive piston geared to revolve at half the speed of the crank-shaft, a gear-wheel and connected insulated disks 55 arranged to turn loosely about the
45 axis of this second shaft, two pairs of electric contacting pins oppositely placed in these disks adapted to move outward and inward, a fixed insulated segmental guide and a revolving contact to close the circuit between
50 the contact-pins in each pair and between electric wires to transmit electric current through these pairs of pins connected thereto, thereby igniting charges in the motive cylinders, in the manner substantially as specified.

60 7. In a gas-engine, two single-acting motive pistons, a double-acting charge-compressing piston, all connected to a common crank-shaft, means to reverse the motion of

the crank-shaft consisting of the revolvable 65 disk or member 55 containing two pairs of diametrically opposite electric contacting pins 59, a gear-wheel to turn this disk and change its relation to the cranks of the engine, segmental toothed racks to engage this gear-wheel and a shaft on which these racks are held to produce coincident action of the parts for each motive engine, a hand-lever and notched segmental bar to lock the lever, reverse the engine and indicate the point 70 of ignition, arranged and operating substantially as described.

8. In a gas-engine, two single-acting motive pistons and a double-acting charge-compressing piston connected to one crank-shaft, 80 pipes and passages connected to these, adjustable electric devices to ignite the charges in the motive cylinders, producing rotation of the engine either way, a cross-shaft to adjust the electric igniting devices simultaneously for each motive engine and connections from this shaft to a valve that permits circulation and attenuation of the fuel-gas when stopping, starting and reversing the engine, 85 substantially as shown and described.

9. In a gas-engine, two single-acting motive pistons and a double-acting charge-compressing piston connected to one crank-shaft by cranks that permit revolution of the engine each way, electric devices to ignite the 95 charges in the motive engines, these devices dual, and the electric contacts adjustable by means of an oscillatory cross-shaft and connections for each motive engine that acts simultaneously, a connection from this shaft 100 to a valve that opens each way and permits circulation and attenuation of the fuel-gas, a hand-lever to adjust this oscillating shaft and a spaced scale to indicate the points of electric contact and ignition each way and at 105 various points, substantially as specified.

10. In a gas-engine, two single-acting motive pistons and a double-acting charge-compressing piston, all connected to a crank-shaft and operating in definite relation one to 110 the other, the charge-compressing piston displacing a volume in excess of the required supply in the motive cylinders respectively, a hand-adjusted valve to permit circulation and return of a portion of the fuel charges 115 and supplementary thereto a second valve with like functions, controlled by centrifugal apparatus and by the engine's speed of revolution, substantially as specified.

In testimony whereof we have signed our 120 names to this specification in the presence of two subscribing witnesses.
